WELL SCREEN STRUCTURE

Richard N. Myers, Houston, Tex., assignor to
Shell Development Company, San Francisco,
Calif., a corporation of Delaware

Application August 31, 1943, Serial No. 500,713

5 Claims. (Cl. 166—5)

This invention pertains to screens used in oil and gas wells, and relates more particularly to a structure adapted to enclose a screen while it is lowered into a well and installed therein, and to facilitate the removal of said screen from the well after a period of production.

It has heretofore been customary to run screens into wells at the end of a tubing or drill pipe string, thus leaving the screen in an exposed or unprotected condition during the lowering and washing operation.

The majority of screen failures result from erosion, which is either directly caused, or largely aggravated by the impregnation of the screen with drilling fluid and other substances and debris present in the well when the screen is being run thereinto. A large proportion of this clogging mud and debris cannot be washed out of the screen while it is being set, or when in place, unless complicated, dangerous and expensive washing operations are undertaken. The operating efficiency and capacity of clogged screens is naturally greatly reduced.

Screens, especially those of the wire-wrapped type, are furthermore often damaged by contact with pieces or fragments of metal or other material attached to the casing and projecting into the well from the inner wall thereof.

Another difficulty attendant the use of screens is that connected with the problem of their removal from wells, especially after protracted periods of operation. Various deposits of clogging matter accumulate between the screen and the walls of the borehole, and form a retaining bond therebetween.

Since liner screens are usually installed with an annular packer positioned somewhat above the apertured portion of the screen, it is customary procedure in such cases to insert an inside cutting tool into the screen liner, and to cut away and remove from the well the upper portion thereof together with the packer. The next step, if sufficient annular space is available, is to lower into the well, at the end of a drill string, an elongated tube equipped with a rotary shoe, i. e., a tubular drill bit having annularly arranged teeth surrounding an internal bore of a diameter larger than that of the screen. This tubular bit is inserted over the top of the screen, and is rotated by means of the drill string, while a liquid is circulated therethrough, to cut a circular path or space around the screen, thus removing the obstructions retaining the screen. This operation, carried in the general manner of ordinary drilling, is known as washing over the screen. When

the screen has been washed over its total axial length and is free of retaining obstructions, it can be readily removed from the well by means of a device such as a spear tool. If there is no sufficient clearance between the screen and the walls of the borehole, or the length of the screen is too great to permit washing over operations, the screen is cut into longitudinal sections by means of an internal cutting tool similar to that used to cut away the packer, and the sections are pulled out of the well separately.

It is therefore an object of this invention to provide a method and apparatus whereby the possibility of injuring or impairing screens during installation operations is eliminated or minimized, and the operations for retrieving said screens from wells in a substantially intact condition are greatly simplified.

It is also an object of this invention to provide a structure comprising a tubular string, a screen attached thereto, a housing slidably enclosing said screen, said housing being adapted to be set or anchored in a well and being provided with a tubular cutting head, whereby said housing may be anchored in a well, the screen forced out of the housing, the well produced through the screen, and the screen finally removed from the well by washing said housing, operated as a rotary cutting head, over the screen to free said screen from obstructing material, in the manner described hereinbelow.

These and other objects of this invention will be understood from the following description, taken with reference to the attached drawings, 35 wherein:

Fig. 1 is a diagrammatic view, partly in cross-section of the present well structure, and Figs. 2-5 inclusive are diagrams schematically illustrating a particular sequence of steps forming the process of this invention.

Fig. 6 is a detailed view of the latch 56 of Fig. 1.

Fig. 1 represents a well 50 provided to a desired level with a casing 30 having a shoe 36. The present well or screen structure is shown in the well in its retracted position, that is, in the position in which it is lowered into the well. A tubing string comprising any desired number of tubing sections 1, joined together by means of couplings 7, is detachably connected at its lower end to a shoe 42, preferably by means of left-hand screw-threads 69. The shoe 42 is preferably of the non-return type, and comprises perforations 60, and a valve 73 held against its seat by means of a spring 77, so that fluid may be circulated into the well through the tubing 1, but

cannot enter said tubing from the well. Instead of the valve 73, the shoe may be provided with any other suitable non-return valve, such as a ball valve. The shoe may also be provided with a plurality of blades 58.

Attached to the shoe 42 by means such, for example, as right-hand screw-threads 65, and surrounding the lower portion of the tubing string 1, is a tubular screen 55, shown for simplicity as provided with apertures or perforations 53, it being understood that any other type of screen, such as screens comprising a wrapping of wire wound on a tubular member or frame, is suitable for the present invention.

The tubular screen 55 has in its upper portion an outwardly enlarged annular shoulder member 45, provided with a clutch or key member 49, adapted to engage a similar clutch or keyway member 57, as will be explained hereinbelow. The shoulder 45 is likewise provided with an annular gland or packing member 47.

Slidably surrounding the screen 55 is a tubular housing member 51, held in fixed relationship with regard to the string 1 by any suitable locking means, such, for example, as one or more frangible pins 11, made of brass, bronze, copper, steel, or other metal or material. The pin 11 is shown as connecting the housing 51 with the coupling 7 of the tubing string, although it is obvious that the same result is achieved by connecting the housing 51 directly to the tubing 1, or to any member forming a rigid structure there-with such for example, as the shoulder 45 of screen 55, as long as the tubing screen assembly can slide downwards within the housing 51 when unlocked, as by the shearing of pin 11.

The housing 51 has in its lower portion an inwardly enlarged annular shoulder member 63, provided with an annular gland or packing member 61, having a fluid-tight fit about the screen 55, and with a clutch or keyway member 57. Upon a sliding downward motion of the screen 55 with regard to the housing 51, the screen shoulder 45 comes to rest on the housing shoulder 63, and the key or clutch members 49 and 57 engage each other to prevent any rotational motion of the screen with regard to the housing 51.

As shown in greater detail in Fig. 6, the housing 51 is also equipped with one or more latches 56, which are forced by springs 83 against the screen 55 through suitably provided openings in the housing 51. Hollow plugs 82 are provided for mounting the springs 83, which force the square-cross section latches against the screen, until the shoulder 85 of the latch and the shoulder 84 of the housing come into contact with each other. A shield 80 is welded in a streamlined manner to the outside of the housing 51 to protect the latches while running the device into the well. The purpose of latches 56 is to permit the enlarged annular shoulder member 45 to pass the latches in a downward direction but not in an upward direction. Thus, when tubing 1 is released from shoe 42, as will be explained below, the well pressure will not be able to force the screen back into the housing.

The housing 51 has also in its upper portion an annular gland or packing member 3, having a fluid tight fit about the tubing string 1. Annular glands 3 and 61 thus provide sealing means for an annular chamber 43 formed between the housing 51 and the tubing string 1, which chamber serves to enclose the screen 55. A port closed by a plug 44 is used to fill said chamber with a

light grease lubricating oil or other suitable protective and non-corrosive substance, which is forced into chamber 43 until the chamber is full so as to prevent any well fluid from leaking into the chamber 43 during the lowering operation. This port may be installed at the lower end of the chamber to enable the pumping of viscous fluids such as grease into the housing as shown in the drawings, or may be installed at the upper end of the chamber immediately below pin 11 to facilitate pouring liquid into the housing. An equalizing vent 13 in the housing may be incorporated at the upper end of the housing to permit of equalization of pressure within and without the housing while lowering into the well. This vent would permit equalization of pressure with negligible mixing of the fluids within and without the housing.

Carried outwardly on the housing 51 is a packer member 15, of any desired and suitable type, which is held in place by a slip bowl 2, slidably surrounding the housing and held in place by shear pin 19.

Slidably fitting over the tapered outward face of the slip bowl 2 are slips 23, adapted to engage the casing 30 upon upward motion. The slips are held in place by means of a ring 8 slidably fitting over the housing and connected by means of guide or friction springs 14 with a slidably locking or latch ring 20 having a notch 26 adapted to receive a pin or pins 39, fixedly attached to the housing.

It is obvious that instead of the packer and slips arrangement described above and shown in Fig. 1, other suitable conventional packer and slips means may be used to achieve the desired purpose as will be shown hereinbelow.

The lower part of the housing 51 has, integral- 40 ly formed therewith, or attached thereto by means such as welding or screw-threads 59, a 45 rotary shoe or a tubular rotary cutting head provided with a plurality of cutting teeth 40. These teeth are annularly arranged around the central bore of the cutting head, which bore is of a diameter sufficiently large to accommodate the tubular screen 55, but preferably smaller than the outside diameter of shoe 42, which is in turn preferably smaller than the outside diameter of the cutting head 32, for purposes to be described hereinbelow. A key element 64, or an equivalent clutch or friction member, is fixedly attached to the screen 55, while a corresponding keyway or clutch element 64a is provided in the cutting head 65 32 to prevent rotation of the screen and housing with regard to each other when the screen is in its uppermost position.

The operation of the present device is as follows:

The screen structure or assembly is run into the well at the end of a tubing or drill string 1. When the casing shoe 36, or other desired position above the setting point is reached, washing may be commenced by pumping a clean fluid down through the tubing 1, the fluid pressure forcing the valve 73 down, and the fluid returning to the surface through the annular space between the screen structure or the tubing and the walls of the well or casing. If any obstruction 70 on the walls of the well impedes the lowering of the string, rotational motion is imparted to the latter, and the teeth 40 and blades 58 cut the obstructions away in the regular drilling manner, the engagement of key 64 with keyway 64a 75 preventing the pin 11 from shearing due to the

torque impressed thereon by said rotary operation.

The well is washed to the final bottom screen position until the formation can be considered clean or until the well shows a tendency to flow. The assembly is then raised to such a position that the packer 15 is slightly above the desired final position, for example, to a position slightly above that shown in the drawings. The tubing 1 is then rotated and the friction of the springs 14 against the casing preventing the latch ring 20 from following this rotation, the latch ring 20 is released from engagement with the pin 39. The assembly is then slightly lowered, the rings 20 and 8 and the slips 23 being still prevented from following this downward motion of the assembly due to the frictional engagement of the springs 14 with the casing. This causes the slips 23 to slide over the tapered face of the slip bowl 2 and to engage and grip the casing 30. A downward pressure on the tubing 1 causes the pin 11 which, by design, has a lower strength than pin 19, to shear. While continuing to wash by pumping, the tubing 1, shoe 42, and screen 55 are then lowered until the whole apertured space of the screen is forced out of the housing 51 and is exposed to the borehole, and the shoulders 45 and 63 of the screen and housing respectively are in engagement with each other. At this time, the screen is at its fully extended position, is locked against rotation by clutches 49 and 57, and is prevented from being forced upwards by well or other pressure by latches 56. The wash pump at the surface is then shut down, and additional weight on tubing 1, applied to shoe 42, is transmitted, by tension, through screen 55, the contacting upper and lower shoulders of 63 and 45, and the housing 51, to pin 19. This will shear pin 19 and thus cause the housing to slide through bowl 2, which is held from downward movement by slips 23, thus expanding the packing 15 against the casing 30, and thus sealing off the flow in the annular space between casing 30 and housing 51.

Clockwise rotation is then applied to the tubing 1, and the lefthand screw joint 69 is thus broken, since the shoe 42 and screen 55 are prevented from rotating by the engagement, through clutch members 49-57, with the rigidly anchored housing 51. After the tubing 1 has been unscrewed at 69 from the shoe, it may be raised to any desired level, or entirely removed from the well, production of the well being effected through the screen, inside of housing 51, and tubing 1 or directly through the casing 30 above the expanded packer 15. The position of the present device in the well, with the string 1 removed, is at this moment diagrammatically shown in Fig. 2, which for clearness omits all unessential details, such as slips, keys and keyways, etc.

After the well has been produced through the screen throughout a period of time, various matter, such as scale, wax, sand, etc., usually accumulates between the screen and the walls of the borehole, as shown at 80, and jams or freezes the screen to the formation.

In order to withdraw the screen from the well, the following operations are resorted to according to the present method:

A conventional inside cutting tool or knife (not shown) is inserted into the housing 51 at the end of a suitable tubing or drill string, and said housing is cut in a horizontal plane somewhat below the packer 15, as shown at 84 in Fig. 3, 75

into an upper and lower portion. A gripping or spear tool 82 is then inserted into the upper portion and said portion is removed from the well.

A similar spear tool, or a double spear tool 86, having slips 86 adapted to engage the housing 51, and slips 90, adapted to engage the screen 55, is then lowered into the well at the end of the tubular string 1, and the slips 86 are engaged with the housing 51 near the upper end thereof, 10 the slips 90 remaining for the moment idle. The slips 86 are shown in the drawings only schematically, and are actually provided with horizontal teeth to support the housing against gravity, and with vertical teeth to transmit a torque there- 15 to, in the general manner shown, for example, in Patent No. 2,242,602 to Watson.

With the slips 86 firmly gripping the housing, a downward pressure is applied to the housing by means of the string for disengaging the key or clutch members 57 and 49, sufficient clearance being provided between the top of the shoulder 45 and the latch 56 to permit this. A rotary motion and a downward pressure are then applied to the housing by means of the string, whereby the latches 56 are milled out by abrasion with the top surface of shoulder 45, and the housing 51 descends further with rotation around the screen, as shown in Fig. 4, the teeth 40 of the cutting head at the lower end of the housing cutting an annular space around the screen 55. Drilling fluid may be circulated down through the string 1 and nipple 94, returning to the surface through the screen 55 and the annular space between the string and the casing.

When the housing and the cutting head have cleared the total axial length of the screen 55 down to the shoe 42, the slips 90 engage the screen 55 from the inside, whereupon the screen and the housing may be raised in a single operation. It is obvious, however, that if it is not desired to use a double spear, the same operations may be carried by means of a single spear, or rather of two single spears, for example, the spear 82 of Fig. 3, and another spear similar thereto, but having a diameter adapted to fit for engagement within the screen 55, the first spear being used for washing over the screen and for removing the housing, and the second for separately removing the screen after the housing had been removed.

It is obvious that in order for the housing 51 to be able to wash over the entire length of the screen while being held by an inside spear, its length must be in excess of that of the screen by a definite amount. Thus, if the axial length of that part of the housing on which the packer 15 is outwardly mounted, and which is later cut away, as shown in Fig. 3, is H_p ; the axial length of that part of the housing which is necessary for internally accommodating the spear 86 is H_s ; and the axial length of the screen is S , then the total length of the housing H must satisfy the expression $H = H_p + H_s + S$ to permit the teeth 40 to reach the top of the shoe 42 before the slips 86 come to bear against the top of the screen, as shown in Fig. 5.

I claim as my invention:

1. A structure for use in wells, comprising a tubular string adapted to be lowered into a well, an elongated tubular member surrounding said string adjacent the lower end thereof, a cutting head at the lower end of said member, frangible means locking said tubular member with regard to said string, a shoe detachably connected to said string below said head, a tubular

screen affixed to said shoe and slidably extending thereabove into the annular space between said string and said tubular member, and packer means outwardly mounted on said tubular bit member for anchoring said member within the well.

2. A structure for use in wells, comprising a tubular string adapted to be lowered into a well, an elongated tubular member surrounding said string adjacent the lower end thereof, a cutting head at the lower end of said member, frangible means locking said tubular member with regard to said string, a shoe detachably connected to said string below said head, a tubular screen member affixed to said shoe and slidably extending thereabove into the annular space between said string and said tubular member, packer means outwardly mounted on said tubular cutting head member for anchoring said member within the well, and stop members carried by said tubular cutting head and screen members adapted to limit the outward axial motion of said screen with regard to said tubular bit member.

3. A structure for use in wells, comprising a tubular string adapted to be lowered into a well, an elongated tubular cutting head member surrounding said string adjacent the lower end thereof, frangible means locking said tubular cutting head member with regard to said string, a shoe detachably connected to said string below said bit, an apertured tubular screen member affixed to said shoe and slidably extending thereabove into the annular space between said string and said tubular cutting head member, annular packing members sealing said space above and below the apertures of the screen, packer and slips means outwardly mounted on said tubular cutting head member for anchoring said member within a well, stop members respectively carried by said cutting head and screen members

adapted to arrest the axial motion of said screen with regard to said cutting head, and key members carried by said cutting head and screen members adapted to prevent a rotational motion of said screen and cutting head with regard to each other.

4. A structure for use in wells, comprising a tubular string adapted to be lowered into a well, an elongated tubular cutting head member surrounding said string adjacent the lower end thereof, frangible means locking said tubular bit member with regard to said string, a shoe detachably connected to said string below said bit, an apertured tubular screen member affixed to said shoe and slidably extending thereabove into the annular space between said string and said tubular cutting head member, annular packing members sealing said space above and below the apertures of the screen, packer and slips means outwardly mounted on said tubular cutting head member for anchoring said member within a well, stop members respectively carried by said cutting head and screen member adapted to limit the outward axial motion of said screen with regard to said tubular cutting head member, key members carried by said cutting head and screen members adapted to prevent a rotational motion of said members with regard to each other, and latch means carried by tubular cutting head member adapted to lock said screen against inward axial motion with regard to said tubular cutting head member.

5. In combination with a well screen attached to the end of a tubular string, a tubular member slidably surrounding said screen, the lower end of said member being provided with annularly arranged rotary teeth, locking means frangibly securing said member with regard to the string, and means comprising a packer and slips for anchoring said member within a well.

RICHARD N. MYERS.
